(57) **CLAIM**

I claim the ornamental design for a bag convertible into a towel or blanket, as shown and described.

DESCRIPTION

FIG. 1 is a perspective view of a closed configuration showing our new design according to a first embodiment.

FIG. 2 is a front view of a closed configuration showing our new design according to the first embodiment.

FIG. 3 is a top view of a closed configuration showing our new design according to the first embodiment.

FIG. 4 is a back view of a closed configuration showing our new design according to the first embodiment.

FIG. 5 is a bottom view of a closed configuration showing our new design according to the first embodiment.

FIG. 6 is a left side view of a closed configuration showing our new design according to the first embodiment.

FIG. 7 is a right side view of a closed configuration showing our new design according to the first embodiment.

FIG. 8 is a view showing our new design according to the first embodiment, in particular showing a front view of a partially open configuration showing an underside of a top flap.

FIG. 9 is a view showing our new design according to the first embodiment, in particular showing a front view of a partially open configuration showing the underside of the top flap and a partially unfolded bottom portion.

FIG. 10 is a view showing our new design according to the first embodiment, in particular showing a front view of a partially open configuration showing the underside of the top flap and a partially unfolded bottom portion further unfolded to the right.

FIG. 11 is a view showing our new design according to the first embodiment, in particular showing a front view of a partially open configuration showing the underside of the top flap and a partially unfolded bottom portion further unfolded to the left; and,

FIG. 12 is a view showing our new design according to the first embodiment, in particular showing a front view of a fully open configuration.

The broken lines shown in the drawings represent unclaimed portions of the design.
